UNITED STATES PATENT OFFICE.

ANDRÉ VIRGILE PAUL MARIE BERTHIER, OF NEUILLY-SUR-SEINE, FRANCE,
ASSIGNOR TO UNITED STATES MACHINE GUN COMPANY, OF BOSTON, MASSA-
CHUSETTS, A CORPORATION OF MASSACHUSETTS.

FIREARM.

1,366,863.

Specification of Letters Patent. Patented Jan. 25, 1921.

Application filed May 28, 1917. Serial No. 171,373.

To all whom it may concern:

Be it known that I, ANDRÉ VIRGILE PAUL MARIE BERTHIER, a citizen of the Republic of France, and a resident of Neuilly-sur-Seine, in the French Republic, (whose post-office address is 15bis Rue d'Orléans, Neuilly-sur-Seine, France,) have invented an Improvement in Firearms, of which the following description, in connection with the accompanying drawings, is a specification, like characters on the drawings representing like parts.

This invention relates to fluid operated apparatus and has for its object more particularly to provide means whereby the fluid flow or pressure may be controlled or variably adjusted as circumstances may require.

It is a well known fact that the efficiency of fluid operated apparatus varies and may be seriously affected by changes of conditions. Thus it has been found that the operation of gas operated firearms, such as machine guns, is appreciably affected by changes in climatic conditions and changes of altitude, particularly the latter. It is found, for example, that as the altitude at which a gas operated machine gun is operated increases, the efficiency of the gun decreases in proportion, and if the change from a lower to a higher altitude is sufficiently great the gas pressure which served for an efficient operation of the gun at the lower altitude will no longer suffice, the speed of operation of the gun, for example, falling off to such a degree as greatly to impair its effectiveness. My invention, by rendering the gas flow or pressure adjustable overcomes this defect.

The objects and aims of the invention will best be understood from the following description, taken in connection with the accompanying drawings, of several forms or embodiments of the invention shown and described for illustrative purposes, it being understood that the invention in its true scope is definitely set forth by the claims.

In the drawings:

Figure 1 is a longitudinal, vertical, sectional elevation of the breech portion of a machine gun containing the operating mechanism;

Fig. 2 is a longitudinal, vertical section through the barrel and part of the operat-

ing mechanism of a machine gun, and showing one illustrative embodiment of my invention applied thereto;

Fig. 3 is a side elevation of said embodiment of my invention;

Fig. 4 is a vertical cross section on line 4—4 of Fig. 3;

Fig. 5 shows the breech block and extractor;

Fig. 6 is a sectional detail of the breech block, firing pin, gas piston and connecting parts, on line 6—6 of Fig. 1;

Fig. 7 is a detail of the means for retaining the cylinder 154 in place;

Fig. 8 shows a further illustrative embodiment of my invention;

Fig. 9 shows a further illustrative embodiment of my invention in which the radial passages in the cylinder 154 are arranged in different transverse planes or substantially in a helical line or plane;

Fig. 10 shows a key which may be used to rotate the cylinder 154; and

Fig. 11 shows said key in use.

My invention is herein conveniently shown applied to the machine gun of my Patent No. 1,083,872 of January 6, 1914, but it will be apparent that my invention is equally applicable to any other gas operated machine gun. Only so much of the mechanism and structure of the gun and its mode of operation will be described herein as is necessary to an understanding of the present invention, it being understood that the said structure, mechanism and mode of operation are fully described in my patent above referred to, to which reference is made for a more detailed description thereof.

In the embodiment of the invention herein shown, a portion of the gases generated by the explosion pass from the bore 2, Fig. 2, of the barrel 3 through a passage 4 into a gas chamber or cylinder 6 in which is an actuating member to be operated by said gases, said member herein consisting of a piston 8 having a reduced head 10 of a diameter to fit closely within the fore part 12 of the cylinder 6 when said piston is in its forward position. The passage 4 is provided partly in the wall of the barrel and partly in a suitable part or block 14 which may be secured to the barrel or formed integral therewith. The rear portion of the piston 10

is bored at 16 to receive a helical spring 18 which bears at its front or right end, referring to Fig. 1, against the bottom of said bore, and at its rear end against a part of 5 the frame 20 of the gun. A pin 22 screw-threaded into the frame at 24 extends into the bore 16 of the piston and for a certain distance within the spring 18, to serve as a 10 guide for the latter when the piston is driven forward by its spring.

The breech block 26 is reciprocated within the frame 28 by the piston 10 and is suitably guided within said frame, all as fully explained in my patent above referred to. To 15 reciprocate the breech block, the piston 10 is provided near its rear end, Fig. 1, with an upwardly projecting plate 30 having upon each side near its upper end a laterally projecting nipple 32. The plate 30 extends upwardly between two parallel plates 34, 34 extending downwardly from the cylindrical portion 36 of the breech block and each provided with a slot 38, each of said slots being adapted to be engaged by one of the nipples 32, see Fig. 5. The opening of said 20 slots 38, both vertically and horizontally, is somewhat greater than the height and width of said nipples 32, and from each of said slots there extends downwardly in an inclined direction to the front edge of each of the plates 34, a guide groove 40, the lower edges 42 of said grooves starting from the lower edges of the slots 38, 38, but the upper edges 44 of said grooves 40 starting slightly 25 below the upper edges of said slots 38, 38, thus leaving a shoulder 46, 46, adapted to be engaged by said nipples 32, it being understood that the guide grooves 40, 40 are of a width to allow free passage along them of 30 said nipples 32, when the latter are in the lower ends of the slots 38.

The firing pin 48 is mounted for sliding movement in a suitable chamber 50 provided in the breech block 26, and when projected 45 forwardly its front end 52 projects sufficiently from an opening 54 in the front end of the breech block to explode the cartridge that is in the cartridge chamber of the gun, a shoulder 56 upon the firing pin co-operating 50 with a shoulder 58 of the breech block to limit the forward movement of the firing pin in the latter. Movement of the firing pin 48 in the breech block is effected by the piston 10 by means of the plate 30 which is 55 loosely embraced between two abutments 60 and 62 extending downwardly from the firing pin 48 into the space between the two plates 34, 34 through a longitudinal opening or slot provided in the lower wall of the 60 firing pin chamber 50 of the breech block between said plates 34, 34.

The head 64 of the breech block is pivoted to the main body of the breech block by a pin 66 and is guided laterally through the 65 two cheeks 68, 68 which embrace the front

abutment 70 of the main body of the breech block, which latter is adapted to swing about said pivot 66, while the head 64 moves in a suitable guide provided in the casing 28 and has no vertical movement, all as fully explained in my patent above referred to. The two parallel plates 34, 34 extending downwardly from the breech block are connected at their rear lower ends by a transverse wall 72, with which a projection 74 on the piston 75 co-operates to assist in the forward movement of the breech block by the piston. Rearward movement of the breech block is effected by a shoulder 76 which co-operates with a downwardly projecting abutment 78 80 on the breech block, through an elastic buffer 80. The breech block is provided upon its under side with an inclined cam surface 82 forward of the abutment 78 and upon its upper surface with a projection 84, the functions of which will be hereinafter more fully described. 85

The trigger mechanism consists of a recessed sear 86 which is adapted to oscillate upon a pin 88 and whose rear arm is provided with a plate 90 acted upon by a spiral spring 92. This sear engages a tooth 94 on the under side of the piston in the case of individual firing. A second sear 96 pivoted at 98 carries the trigger 100 and is acted 95 upon at its rear end by a spring 102. This sear 96 carries between the point where it is acted upon by the spring 102 and its pivot 98, a reinforcement 104, having a recess to receive one end of a spring 106, the other 100 end of which is received in a recess provided in a catch 108, which is adapted to swing about a pivot pin 110. This sear 96 co-operates with a tooth 112 situated back of the tooth 94 upon the under side of the 105 piston 10.

The cartridges are contained in a magazine 114 which is inserted from above into a bearing sleeve 116, the cartridges being pressed downwardly by a fan-shaped spring 110 118 acting upon a follower 120 and are presented successively one by one in the path of movement of the breech block 26. For a full description of the construction of the magazine and its operation, reference may be had 115 to my patent above referred to. A more detailed description thereof is not deemed necessary herein for the understanding of the present invention.

A cartridge extractor 124 is mounted on 120 the breech block by means of a pin 126 which engages in a curved recess 128 in the breech block in such manner that the breech block can ascend and descend independently 125 of the cartridge extractor which is guided during its entire course in a longitudinal groove of the breech casing. A reinforcement 130 upon the extractor engages a recess 132 in the right side of the breech block and serves to take up the pull in withdrawing 130

the cartridge case. This extractor is constructed and operated as described in the patent above referred to, to which reference is made for a more detailed description.

5 The gun may be provided with a sliding cocking handle 122, suitable cooling means, shooting stay, etc., all of which may be of the construction and mode of operation described in my patent above referred to and 10 need not be herein more fully described.

The gun is adapted for individual firing as well as for automatic firing, and for this purpose is provided with a rotary key 134 provided with shoulders 136, 136. When 15 this key is turned into the position shown in Fig. 1, one of the shoulders 136 engages the sear 86 and presses it downwardly so as to hold it out of engagement with the tooth 94. In this condition, therefore, only the 20 sear 96 controls the piston by its engagement with the tooth 112 and the gun is adjusted for automatic firing. With the rotary key 134 turned so that neither of the shoulders 136, 136 is in engagement with the sear 86, 25 the piston is controlled by the engagement of both sears with their respective teeth 94 and 112 and the gun is adjusted for individual firing.

Assuming that the gun is adjusted for 30 individual firing, pressure of the finger on the trigger 100 causes the front end of the sear 96 to swing downwardly and the catch 108 to lift the rear end 90 of the sear 86 thus disengaging the sear 86 from the hook 94 of 35 the piston. The spring 18 moves the piston forward until the tooth 112 engages the sear 96 which is still in its path of movement. Continued pressure on the trigger, however, 40 disengages the sear 96 from the hook 112 and the piston 10 is driven forward to its full extent by the spring 18. Furthermore, as the sear 96 releases the hook 112, or immediately thereafter, the catch 108 releases, 45 in the continued backward movement of the trigger 100, the rear end 90 of the sear 86, so that the sear 86 is now free to rise into its original position under the action of its spring 92, and is thus prepared to reengage 50 the tooth 94 on the piston when the latter is returned to its initial position upon the firing of the cartridge.

As the piston is driven forward, as described, by the spring 18, the projection 74 by its engagement with the part 72 of the 55 breech block and the nipples 32 by their engagement with the shoulders 46, 46 on said breech block (Fig. 5) carry the breech block 26 forward in a rectilinear direction until the inclined plane 82 on the lower side of 60 the breech block just in front of the abutment 78 meets the end 138 of the stationary part 140 of the breech cylinder bearing. Hereupon, the inclined plane 82 sliding up onto said part 140 raises the rear end of the 65 breech block by turning it about the pivot or

pin 66, sufficiently to release the nipples 32 from engagement with the shoulders 46, 46 at the upper end of the slots 40, the forward end of the breech block having driven the cartridge home into the cartridge chamber 70

142 and the front end of said breech block being against and closing the entrance to the cartridge chamber and the projection 84 being in vertical alinement with a correspondingly shaped recess 144, in the frame 28. 75

The firing pin 48, which was carried forward with the breech block, has maintained its rearward position therein, but in the continued forward movement of the piston 10, after the breech block has reached the limit 80 of its forward movement as described, the nipples 32 slide along within the inclined slots 40 provided as described in the plates 34, 34 of the breech block, carrying the firing pin 48 forward with them by their engagement with the abutment 60 projecting downwardly from said firing pin. In their move- 85

ment along the slots 40, said nipples 32, first by their engagement with the upper inclined edges 44 of said slots 40 further raise the 90 rear end of the breech block firmly to seat the projection 84 within the recess 144 of the frame, thus locking the breech block against rearward movement, and then project the front end 52 of the firing pin through the 95

opening 54 in the front end of the breech block and into contact with the primer of the cartridge, thus exploding the latter. A part of the explosion gases passes from the bore 2 through the passage 4 (Fig. 2) into the fore 100

part 12 of the cylinder 6 and thus drives the piston 10 to the rear against the action of the spring 18 into the position shown in Fig. 1, when the sear 86 snaps upwardly in front of the tooth 94 and holds the piston in its 105

rearward position, the gases escaping from the cylinder 6 through the openings 146. The trigger being released, the sear 96 is returned to its normal position by the spring 102 and engages in front of the tooth 112. 110

In this rearward movement of the piston 10, the nipples 32 carried thereby move rearwardly along the slots 40, thus withdrawing the firing pin 48 into the breech block and by their engagement with the lower inclined 115

edges 42 of said slots lowering the rear end of the breech block about the pivot 66 to disengage the projection 84 on said block from the recess 144 of the frame, and the buffer 80 on the projection 76 of the piston then 120

engages the abutment 78 on the breech block and carries the latter back to its rearward position shown in Fig. 1, the projection 74 engaging behind the part 72 of said breech 125

block and the nipples 32 behind the shoulders 46, 46 at the upper ends of the slots 40, ready to carry the breech block forward again when the trigger is again pulled, another cartridge having meanwhile been 130

brought into position by the spring 118 to 130

be engaged by the forward end of the breech block in the latter's next forward movement. In this rearward movement also of the piston, the cartridge extractor extracts the exploded shell which is ejected by the ejector, as fully described in my earlier patent above referred to.

As already stated, to adjust the gun for automatic firing, the rotary key 134 is turned into a position wherein one of the shoulders 136 thereon engages the sear 86 and presses it downwardly so as to prevent it from engaging with the piece 94. If the trigger be now pulled back, the sear 96 by which the piston is now controlled will be disengaged from the tooth 112 of the piston, and the piston will continue to reciprocate and the above described movement of the mechanism will be repeated as long as the pressure on the trigger continues, or as long as there are cartridges in the magazine. When the last cartridge is ejected, the piston comes to rest in its forward position and the mechanism is then cocked again by the aid of the cocking handle 122, which is slidingly mounted on the underside of the frame (Fig. 1) and is provided with a projection 148 adapted to engage a projection 150 on said piston 10, so that by pushing the handle 122 backwardly the piston will be returned to its rearward position and then held by the sear, all as fully described in my patent above referred to.

In Figs. 2, 3 and 4 is shown means for adjusting or varying the flow or pressure of the operating gases for the piston 10, said means herein comprising throttling means. Said throttling means may comprise an adjustable member, which in that illustrative embodiment of the invention shown in said figures consists of a cylinder 154 fitted for rotary movement in a transverse cylindrical opening 152 provided in the block 14. Said cylinder is provided with a central bore 156, open to atmosphere at both ends, which may be the right end referring to Fig. 4. With this central bore 156 of the cylinder 154 there communicate a plurality of passages extending radially from said central bore 156 to the periphery of the cylinder 154. These radial passages are located in the same transverse plane of the cylinder 154 and are of different diameters. Herein seven such radial passages 158, 160, 162, 164, 166, 168 and 170 are provided, but it will be apparent that this number may be varied as may be desirable. A passage 172 leads from the passage 4 to the cylindrical opening 152 in which is fitted the cylinder 154, and by rotating said cylinder the outer end of any one of the radial passages 158 to 170 may be caused to register with said passage 172. The cylinder 154 is provided with a flanged head 174 by which it may be readily rotated. Means are provided to

hold or lock the cylinder 154 in place when any one of the passages 158 to 170 are in register with the passage 172, said means herein comprising a spring pressed pin 176 the head of which is adapted to engage 70 notches 180, 182, 184, 186, 188, 190 and 192 corresponding to the passages 158 to 170, respectively, and disposed in such manner about the periphery of the head 174 that when the pin 176 is in engagement with one 75 of said notches the corresponding radial passage in the cylinder 154 is in register with the passage 172. The pin 176 is guided for longitudinal movement in the block 14 and is provided with a collar 194 between which 80 and the base of the opening in which said pin is mounted there is inserted the helical spring 196 that tends to press the pin outwardly to cause its head to engage any one of the notches 180 to 182 when said notch 85 is brought into register with the head of said pin by rotation of the cylinder 154. To rotate the cylinder 154 it is only necessary to press the pin 176 inwardly against the action of the spring 196 to disengage the 90 head of the pin from that notch in the periphery of the cylinder head 174 with which it is in engagement.

The invention contemplates means for rotating the cylinder 154 when adjustment 95 of the gas pressure is desired, said means being useful at all times but particularly when the cylinder has become heated by the firing of the arm. Said means is preferably adapted also to release the pin 176 from 100 locking engagement with the cylinder head 174, to render rotation of the cylinder possible and to that end said means may conveniently consist of a key substantially as illustrated in Figs. 10 and 11. Referring 105 to said figures, in the illustrative form of the key shown herein, the latter comprises a cylindrical stem or shank 170^a having a transverse piece 173 to act as a handle and a bit 175. In use the end 177 of the stem 110 170^a is inserted in the central bore 156 of the cylinder 154 at the flanged end of the latter, and the end of the bit 175 of said key is applied to the outer end of the blocking pin 176 so that, by pushing the end 177 of 115 the key stem 170^a home into the bore 156 of the cylinder, the bit 175 of the key will push the pin 176 out of engagement with that notch of the cylinder head 174 with which it is in engagement, as shown in Fig. 120 11. The bit 175 of the key being now in engagement with the notch vacated by the pin 176, by turning the key the cylinder 154 can be turned until the next following notch in the head of said cylinder comes into 125 alinement with the pin 176, whereupon the latter will engage said notch under the action of its spring 196 and arrest further rotation of said cylinder. In this way the cylinder 154 can be turned step by step to 130

bring any one of its radial passages 158 to 170 into alinement with the passage 172.

A passage 179 will preferably be provided in the block 14, said passage being in axial 5 alinement with the passage 172, see Fig. 2. This passage 179 facilitates the boring of the passage 172, the boring tool being inserted through the passage 179, the cylinder 154 having been previously withdrawn, and the 10 passage 172 being then readily bored in alinement with said passage 179. The passage 179 also greatly facilitates cleaning of said passage 172 and of the radial passages 158 to 170 of the cylinder 154, for by turning 15 said cylinder said radial passages may be successively brought into register with said passage 179, and any suitable cleaning tool may then be passed through said passage 179 and the radial passage in register 20 therewith to clean the latter.

Accidental withdrawal of the cylinder 154 from the block 14 is prevented by a spring 25 pressed pin 198 mounted for sliding movement in a bore 200 and having its outer end normally maintained by the action of its 30 spring 199 in engagement with an annular groove 201 provided on the periphery of the cylinder 154. The pin 198 is provided with a finger piece 202 projecting outwardly 35 through a slot in the wall of the block 14, by which the pin 198 may be pushed outwardly to withdraw its end from engagement with the groove 201 of the cylinder 154, thus enabling the latter to be removed for cleaning 40 or for any other purpose. That portion of the wall of the block 14 through which the finger piece 202 projects will preferably be countersunk to protect said finger piece from accidental contact in the use of the gun.

40 It will be seen from the above-described construction that at each discharge of the gun a certain amount of the gases generated by the explosion passes from the bore 2 of the barrel through the passage 4 into the 45 front end 12 of the cylinder to drive the piston 10 rearwardly, a certain part of said gases being exhausted into the atmosphere through the passage 172, that one of the 50 passages 158 to 170 which is in register therewith, and the axial opening or bore 156 of the cylinder 154. By varying the amount of the gas thus exhausted, which is herein effected by bringing the radial passages 158 to 170 of different diameter into coincidence 55 with the passage 172, the amount of the gases entering the cylinder 6 through the passage 4 will also be varied.

It will thus be seen that this invention 60 provides means whereby the gas pressure for operating the apparatus or gun may be controlled or adjusted as desired. The pressure may be varied or adjusted to preserve the same gas pressure and therefore the same 65 effectiveness of operation at whatever altitude the gun is used.

The smaller the amount of the gases that is allowed to exhaust through the passage 172, the greater will the amount of the gases be that penetrate into the cylinder 6 from the barrel and the greater therefore will be 70 the force exerted by said gases upon the piston 10. As the altitude at which the gun is used increases the greater must the gas pressure be in order effectively to operate 75 the gun, and therefore while at sea level the cylinder 164 will be adjusted with the passage 170 in alinement with the passage 172, it will be found that as the altitude increases one of the passages 168 to 158 of less diameter according to the altitude attained, 80 should be used.

It will thus be seen that my invention is particularly valuable in machine guns mounted on aeroplanes.

Other conditions may also effect the gas 85 pressure, for example changes of climate or variations in the quality of the ammunition used, but all variations in the gas pressure whether caused by the conditions enumerated or any others may be quickly remedied 90 by the use of my invention and that gas pressure secured or maintained as is best suited for the effective operation of the gun.

In Fig. 8, a modified construction is shown. Here the radial passages 158 to 170 95 in the cylinder 154 are replaced by peripheral grooves 203, 204, 205, 206 and 208, which by rotation of the cylinder 154 may each be brought into alinement with a passage 210 extending from said passage 4 100 transversely of said cylinder 154 in the same transverse plane as said grooves 203 to 208 and opening into the atmosphere at 212. Said passage 210 intersects the cylinder 154 substantially to the width of said passage. 105 In all other respects, the construction may be the same as that shown in Figs. 2 to 4. It will be seen that the shallowest groove in the cylinder 154 is the groove 203 and the deepest the groove 208, and it will be apparent that the shallower the groove that is brought into coincidence with the passage 210 the less will be the exhaust and the greater will be the gas pressure in the cylinder 12, and vice versa.

In Fig. 9 is shown a construction in which the radial passages 158 to 170 are disposed in different planes or substantially in a helical line or plane in the cylinder 154, and the latter has screw-threaded engagement 110 at 181 with the screw-threaded inner wall of the cylindrical opening 152, the pitch of the screw threads and that of the helical line in which the radial passages 158 and 170 are disposed being the same. When the cylinder 154 is screwed entirely home, none of the radial passages 158 to 170 coincides with the passage 152, the latter being thus closed by the wall of the cylinder 154, but by unscrewing the cylinder said radial passages 115 120 125 130

- may be brought successively to coincide with said passage to vary the gas pressure, said radial passages being of course of different diameter as in the construction previously described, herein seven radial passages are provided with corresponding notches upon the periphery of the head 174 to be engaged by the pin 176 and hold the cylinder in adjusted position, and also the 10 axial bore 156 in said cylinder into which the helically arranged radial passages open. In this construction, the pin 198 and annular groove 201 may be omitted, as the screw threaded engagement of the cylinder with 15 the block 14, in conjunction with the engagement of the locking pin 176 with the notches in the flanged head 174 of the cylinder prevent accidental withdrawal of the latter.
- 20 The gun may be used with the cylinder 154 screwed home, that is to say with the passage 172 closed where conditions warrant it.

It will be apparent that in the construction shown in Fig. 9, the radial passages in the cylinder 154 could be replaced by the peripheral passages or grooves shown in Fig. 8, said peripheral grooves being however disposed in a helical line around the 30 periphery of said cylinder.

The gas or pressure controlling means embodying my invention is simple in construction and operation. There are no parts to get out of order, and the cylinder 35 154 is easily and quickly removable, and when removed the parts are readily accessible for cleaning. The cylinder is as easily and quickly replaced and there is practically no chance of its being accidentally 40 displaced after it has been adjusted in the position desired.

It will be apparent that while the invention has herein been described as embodied in the details illustrated, the invention is 45 not to be considered as circumscribed or limited to these details, or any of them, since they may be variously modified within the true scope of the invention which is definitely set forth by the claims.

50 Claims.

1. In a gas-operated firearm, in combination, means actuated by the explosion gases to operate the firearm; conducting passages to conduct the gases from the bore of 55 the firearm to said actuating means and to the atmosphere; and a gas pressure controlling member adapted to coöperate with one of said conducting passages and provided with a plurality of passages of different 60 diameter disposed in different transverse planes, said controlling member being rotatable and movable axially to cause any one of its passages to coöperate with said conducting passage.

65 2. In a gas-operated firearm, in combina-

tion, means actuated by the explosion gases to operate the firearm; conducting passages to conduct the gases from the bore of the firearm to said actuating means and to the atmosphere; and a gas pressure controlling member adapted to coöperate with one of 70 said conducting passages and provided with a plurality of radial passages of different diameter disposed in different transverse planes, said controlling member being rotatable and movable axially to cause any one of its 75 passages to coöperate with said conducting passage.

3. In a gas operated firearm, in combination, means actuated by the explosion gases 80 of the firearm to operate the latter; a casing; gas passages leading from the bore of the firearm to said actuating means and to the atmosphere; a gas pressure controlling rotary member provided with a plurality of 85 passages of different diameter disposed in a substantially helical line in said member, said rotary member having screw-threaded connection with said casing, by means of a screw-thread of substantially the same pitch 90 as that of the helical line in which the passages are disposed in said member, so that by rotation of said member any one of the 95 passages therein may be caused to coöperate with said conducting passages; and means to lock said rotary member in adjusted position.

4. In a gas-operated firearm, in combination, means actuated by the explosion gases 100 of the firearm to operate the latter; a casing; gas passages leading from the bore of the firearm to said actuating means and to the atmosphere; a gas pressure controlling rotary member provided with a plurality 105 of radial passages of different diameter disposed in a substantially helical line in said member, said rotary member having screw-threaded connection with said casing, by means of a screw-thread of substantially the same pitch as that of the helical line in 110 which the radial passages are disposed in said member, so that by rotation of said member any one of the radial passages 115 therein may be caused to coöperate with said conducting passages; and means to lock said rotary member in adjusted position.

5. In a gas-operated firearm, in combination, a gas cylinder; a piston contained in 120 said cylinder and adapted to be actuated by the explosion gases from the bore of the 125 firearm; a passage leading from said bore to said cylinder; means, including an adjustable rotary cylinder provided with a plurality of passages of different diameter disposed in a substantially helical line in 125 said rotary cylinder, for varying the amount of explosion gases acting upon said piston, said rotary cylinder being also movable axially to cause any one of its passages to coöperate with the passage leading from the 130

bore of the firearm to the gas cylinder; and means to lock said rotary cylinder in adjusted position.

6. In a gas-operated firearm, in combination, a gas cylinder; a piston contained in said cylinder and adapted to be actuated by the explosion gases from the bore of the firearm; a passage leading from said bore to said cylinder; means, including an adjustable rotary cylinder provided with a plurality of radial passages of different diameter disposed in a substantially helical line in said rotary cylinder, for varying the amount of explosion gases acting upon said piston, said rotary cylinder being also movable axially to cause any one of its radial passages to coöperate with the passage leading from the bore of the firearm to the gas cylinder; and means to lock said rotary cylinder in adjusted position.

7. In a gas-operated firearm, in combination, means actuated by the explosion gases of the firearm to operate the latter; adjustable means to vary the amount of the explosion gases acting upon said operating means; means to retain said adjustable means in adjusted position; and a combined releasing and adjusting key, separate from the firearm and constructed and arranged to be applied to said adjustable means and when applied thereto to engage and release said retaining means and engage said adjustable means so that it can be adjusted by said key.

8. In a gas-operated firearm, in combination, means actuated by the explosion gases of the firearm to operate the latter; a conducting passage leading from the bore of the firearm to said operating means; a rotary cylinder provided with a plurality of passages of different diameter, each of which can be caused to coöperate with said conducting passage by rotation of said cylinder; means to lock said cylinder in adjusted position; and means separate from said firearm and constructed and arranged to be applied to said cylinder for first releasing said locking means and then turning said cylinder to bring one of the pas-

sages in the latter out of coöperation with 50 said conducting passage and bring another into coöperation therewith.

9. In a gas-operated firearm, in combination, means actuated by the explosion gases of the firearm to operate the latter; a conducting passage leading from the bore of the firearm to said operating means; a rotary cylinder provided with a plurality of 55 passages of different diameter, each of which can be caused to coöperate with said conducting passage by rotation of said cylinder; a locking pin automatically to engage a notch in the periphery of said rotary cylinder and lock the latter in place, whenever one of the passages in said cylinder 60 is in position to coöperate with said conducting passage; and means for first disengaging said pin from the peripheral groove of said cylinder and then rotating the latter to cause another passage therein 65 to coöperate with said conductive passage.

10. In a gas-operated firearm, in combination, operating means adapted to be actuated by pressure of the explosion gases to operate the firearm; and means, comprising 75 a member provided with a plurality of gas passages disposed in different transverse planes, said member being adjustable to render said passages selectively operative to vary the gas pressure acting on said fire- 80 arm operating means.

11. In a gas-operated firearm, in combination, means actuated by the explosion gases to operate the firearm; gas passages to conduct the gases from the bore of the 85 firearm to said actuating means and to the atmosphere; and a gas pressure controlling member adapted to coöperate with one of said gas passages and provided with a plurality of passages of different diameter disposed in different transverse planes, said controlling member being adjustable selectively to cause any one of its passages to coöperate with said gas passage.

In testimony whereof I have signed my 95 name to this specification.

ANDRÉ VIRGILE PAUL MARIE BERTHIER.
